UNITED STATES PATENT OFFICE.

RUFUS M. STONE, OF OKLAHOMA CITY, OKLAHOMA.

HYDROCARBON BURNER.

Application filed June 18, 1924. Serial No. 720,852.

To all whom it may concern:

Be it known that I, RUFUS M. STONE, a citizen of the United States, residing at Oklahoma City, in the county of Oklahoma 5 and State of Oklahoma, have invented new and useful Improvements in Hydrocarbon Burners, of which the following is a specification.

My present invention pertains to hydro- 10 carbon burners for cooking and heating use; and it consists in the peculiar and advantageous burner hereinafter described and definitely claimed.

In the accompanying drawings, forming 15 part of this specification:—

Figure 1 is a side elevation of my novel burner.

Figure 2 is a top plan view of the same partly in section with the oil inlet pipe in 20 elevation.

Figure 3 is a diametrical section of the burner, taken in the plane indicated by the line 3—3 of Figure 1.

Similar numerals of reference designate 25 corresponding parts in all of the views of the drawings.

Among other elements my novel burner comprises an annular member 1 of trough-type which when desired may be disposed 30 on the grate bars at the bottom of a fire box in a stove. The said annular member 1 is provided at 2 with an inwardly reaching flange and is also provided at 3 with an outwardly extending arm in which is an aperture 4.

In addition to the annular member 1 the burner comprises an intermediate member 5. The said intermediate member 5 is made up of a circular body which is concavo-convex and is arranged with its convex side uppermost. On the said convex upper side of the member 5 is a central upstanding teat 6, and ribs 7 which extend from the base of the said teat 6 to the periphery of 45 the body as illustrated. At its underside the body of the intermediate member 5 is provided with supporting legs 8, designed to rest on the flanged portion 2 of the annular member 1 and provided with depending reduced portions 9' adapted to rest within and against the said flanged portion 2 so as to preclude casual displacement of the intermediate member 5 without interfering in any measure with the facility

with which the said member 5 may be dis- 55 associated from the member 1 when necessary. It will also be noticed that by virtue of the legs 8 the body of the intermediate member will be maintained in spaced relation to the upper side of the annular member 1 so that openings between the legs 8 will be afforded intermediate of the body of the member 5 and the upper side of the member 1 as appears in Figures 1 and 3.

Associated with the annular or base member 1 and the intermediate member 5 is a crown member 9, and at this point I would have it understood that all three of the members 1, 5 and 9 referred to are preferably of cast iron. The crown member 9 is 65 of general concavo-convex shape and is provided with a marginal pendent flange 10 at the inner side of which is a shoulder 11 which rests on the ribs 7 of the member 5 and thereby affords a space 12 between the 70 member 5 and the crown member 9. In the center of its underside the crown member 9 is chambered at 13 to accommodate the teat 6 of the intermediate member 5, the wall of the said chamber 13 being spaced from the 75 teat 6 as clearly appears in Figure 3. Extending upwardly from the chamber 13 is a threaded bore 14 in an upstanding boss 15. The said bore 14 is for the reception and connection of the pendent portion of an elbow 16 which together with pipe sections 80 17 and 18 and another elbow 19 constitutes the generator of the burner, the said elbows and pipe sections being preferably of iron.

At the lower end of the pipe section 18 is a 85 union 20 which rests on the arm 3 of the annular base member 1 and serves for the connection of an appropriate bushing 21 utilized in the connection of an oil or hydrocarbon line 22, which preferably extends 90 through the grate before referred to and out of the ash door where it may be equipped with a control valve (not illustrated). The hydrocarbon is in the said generator converted into vapor by the flame coming in 100 contact with the upright portion of the generator which stands full of hydrocarbon, and hence carbonization is prevented. The heated vapor or gas is lead over the members 1, 5 and 9 of the burner into the space 105 12 between the intermediate member 5 and the crown member 9, the hydrocarbon or gas being confined between the members 5

and 9, and the oil or gas being released at the edges of the members 5 and 9 where the hydrocarbon or gas will come in contact with the flame. The crown member 9 fits snugly so that when the burner is heated, said crown member 9 completes the generation of the hydrocarbon into dry gas conducive to a smokeless flame of high heat quality.

10 The intermediate member 5 forms a hot air chamber between the crown member 9 and the member 1 which conduces to adequate generation of the hydrocarbon into gas. The said intermediate member serves 15 to check the hydrocarbon and distribute the same between the ribs, and is also adapted to permit oil that is not generated in the gas to run into the annular member or generating pan 1 where the oil will be consumed. The member or generating pan 1 is, of course, used for generating or heating incident to the starting of the fire. The opening through the central portion of 20 the annular member or pan 1 permits the upward passage of abundant air for the purpose of promoting combustion, the air passing outwardly between the legs 8 and under the edge portions of the intermediate and crown members. Clay is preferably 25 used under and around the burner to form its foundation, and it is to be noticed particularly that in virtue of the construction of the burner, the pipe 22 may be of copper. It is also to be noticed that the burner is 30 susceptible of being properly and readily 35 installed by an unskilled mechanic.

I have entered into a detailed description 40 of the construction and relative arrangement of the parts embraced in the present and preferred embodiment of my invention in order to impart a full, clear and exact understanding of the said embodiment. I do not desire, however, to be understood as confining myself to the specific construction and relative arrangement 45 of parts inasmuch as in the future practice of the invention various changes and modifications may be made such as fall within the scope of my invention as defined in my 50 appended claims.

Having described my invention, what I claim and desire to secure by Letters-Patent, is:

1. A hydrocarbon burner comprising an annular member or pan of trough-type having a flange reaching inwardly from the upper edge of the inner wall of its trough and also having on the upper edge of the outer wall of its trough an outwardly extending apertured arm, an intermediate member having a body of concavo-convex cross-section and also having at the underside of said body shouldered legs resting on said flange of the annular member and further having at its upper side a central upstanding teat and ribs extending from said teat to its edge, a crown member of general concavo-convex form having a pendent and interiorly shoulder flange to bear on said ribs and also having a central chamber the wall of which is spaced from said teat and a threaded socket extending upwardly from said chamber, a generator formed of pipe sections and elbows and a union and having one of the elbows threaded into said socket and the union superimposed on the arm of the annular member, and a pipe line connected with said union by a connection disposed in and extending through the aperture in the arm of the annular member.

2. In a hydrocarbon burner, the combination of an annular member or pan of trough-type, an intermediate member having pendent legs bearing on the inner portion of said annular member and also having a central upstanding teat and ribs extending from said teat to its edge, a crown member supported on said ribs and spaced from the major portion of the intermediate member and having a central chamber the wall of which is spaced from said teat, and a generator connected to and supported on the annular member and extending above and in spaced relation to the annular and crown members and connected with the crown member and communicating with the central chamber thereof.

In testimony whereof I affix my signature.

RUFUS M. STONE.
